UNITED STATES PATENT OFFICE.

DICKERSON G. BAKER, OF WILLIMANTIC, CONNECTICUT, ASSIGNOR, BY
MESNE ASSIGNMENTS, TO THE AMERICAN THREAD COMPANY, OF
JERSEY CITY, NEW JERSEY, AND NEW YORK, N. Y.

THREAD-WINDER.

SPECIFICATION forming part of Letters Patent No. 643,583, dated February 13, 1900.

Application filed June 15, 1898. Serial No. 683,490. (No model.)

To all whom it may concern:

Be it known that I, DICKERSON G. BAKER, a citizen of the United States, and a resident of Willimantic, in the county of Windham and State of Connecticut, have invented certain new and useful Improvements in Thread-Winders, of which the following is a full, clear, and exact description, whereby any one skilled in the art can make and use the same.

10 My invention relates to the class of machines used for winding bobbins or the like which have an extended use in connection with sewing-machines; and the object of my invention is to provide a machine of this class which shall have increased facilities for turning off work both as to the amount of work done in a given time and also as to the quality of the work produced.

20 To this end my invention consists in the device as a whole, in the combination of parts making up the device, and in the details of such parts and their combination, as herein-after described, and more fully pointed out in the claims.

25 Referring to the drawings, Figure 1 is a detail front or end view of my improved thread-winder with the parts in relative position at a preliminary step in the operation of winding. Fig. 2 is a detail top view of that 30 end of the machine containing the winding-spindle and thread-guide. Fig. 3 is a front or end view of the machine, showing the position of the guide with reference to the spindle when the bobbin is nearly wound. Fig. 4 is a detail view showing the means for 35 holding the guide-support in its swinging movement. Fig. 5 is a side view of the machine. Fig. 6 is a front or end view of the machine, showing the relative position of the 40 parts when a bobbin is nearly wound, but in this instance the spindle containing the bobbin being moved away from the guide.

45 Various forms of machines may be employed the mechanism of which will embody my invention, a simple device for carrying out the main features being described herein and illustrated in the drawings, in which the letter *a* denotes the base of a machine, *b* a

standard thereon, and *c* a main shaft driven from any suitable source of power, as by 50 means of a belt *d*, passing over the pulley *c*.

Projections *b'* of cylindrical form extend from opposite sides of the standard *b*, an opening for the shaft *c* extending through the standard and these projections. If desired, 55 the projections may consist of a sleeve located within the standard and projecting on opposite sides thereof.

A winding-spindle support *e*, mounted on one of the projections *b'*, extends upward 60 above the standard and supports above the standard a winding-spindle *f*. This winding-spindle is provided with any suitable means for retaining thereon a core upon which a mass of thread is formed, a gear *f'* on the 65 spindle meshing with a winding-spindle gear *c'* on the main shaft *c*. A guide-support *g* is constructed in the form of a gear-casing and is located on a projection *b'*, preferably on the opposite side of the standard from the 70 winding-spindle support *e*. The upper end of the support *g* bears a guide-stud *h*. A rotary guide *k* is rotatively mounted at the upper end of the guide-support, and a gear *h'* is operatively connected with the guide. It is 75 also connected with the guide-gear *c* on the main shaft by means of an intermediate gear *i*. In the form of the device shown the gears *c*, *h'*, and *i* are located in a recess in the guide-support that forms a casing for the 80 gears. The guide-stud *h* is secured in the upper end of the guide-support, the gear *h'* being rotatively mounted thereon and having a hub, on which is secured the guide *k*. I contemplate any means, however, for operatively 85 connecting the guide and gear and do not limit myself to this precise form.

The supports *e* and *g* are located on the projections *b'* in a manner to have a swinging movement thereon, a device that will allow 90 the supports to have a swinging movement under pressure being employed, this device, however, being sufficient to hold the support in any position once attained. One form of device for accomplishing this result 95 is shown herein, consisting of a clamp-screw

g', located in the guide-support *g*, its inner end resting against a block *g*², a shoe, preferably of leather or other fibrous material, being located between the block and the projection *b'*. It is understood that a similar device is used in connection with the support *e*.

- The rotary thread-guide *k* is round in form and bears in its periphery a guide-slot *k'*, extending in a helical path part way only 5 around the guide and then backward in a like path to the point of beginning. A bridge *l*, consisting of a hood-like extension, projects from the guide-support *g* in a position adjacent to the guide *k* and may be secured to 10 the guide-support in any suitable manner. This bridge underlies the thread-guide and extends upward in a position between the guide and winding-spindle, the edge of the bridge being preferably so located as to cause 15 the thread to pass from the guide over the edge of the bridge onto the bobbin.

In the operation of winding the thread passes through the guide-slot in the guide over the edge of the bridge and onto the winding-spindle, the winding-spindle and guide being rotated with especial reference to each other to produce the kind of "wind" desired. 20 An important feature of invention in connection with the rotary thread-guide resides in 25 maintaining the same angular velocity of the guide and bobbin with respect to each other throughout the entire operation of winding, and by "angular velocity" I mean that the number of revolutions of one part with respect 30 to the other during a given period shall be maintained. This term "angular velocity" is distinguished from "peripheral velocity" as in a case where one body is rotated by direct contact with another, one of which gradually 35 increases in size, in which case the revolution of the part increasing in size would decrease in speed with respect to the opposite part as the operation proceeded. This is an objection in devices where the guide is rotated by direct 40 contact with the bobbin, as it is obvious that by changing the relative angular velocity of the two parts the traverse is changed and would not be the same at the completion of the winding of a bobbin as when the operation 45 began.

In this class of devices it is of advantage to have the guide and the winding-spindle operated from a single source, such a construction enabling the degree of relative rotation 50 of the parts to be easily graduated to a nicety. In such a device it is desirable to rotate the guide slightly faster than the winding-spindle in order that the thread in its spiral wrap about the bobbin shall be carried forward to 55 a slight degree and thus prevent the objectionable feature of the tendency of the thread as it wraps about the bobbin to ride over that part previously wound thereon, as is the case where the bobbin and guide are rotated at 60 the same rate. Such objection is easily obviated in a machine of this description by

varying to a slight degree the number of teeth in the gears between the driving-shaft and the winding-spindle or guide-spindle, as it is obvious that this change must be very slight. 70 In winding some forms of thread, as on a bobbin of considerable length, it is found desirable to move the spindle away from the guide instead of the guide away from the spindle, and in the form of the device herein shown 75 I have provided means whereby this result may be obtained, the spindle being moved away from the guide or the guide moved away from the spindle, as desired.

I claim as my invention—

1. In a machine for winding thread or the like, a standard, a main shaft mounted in the standard, means for driving the main shaft, a projection extending from each side of the standard, a swinging bracket located on one 85 of said projections, a thread-guide shaft and thread-guide mounted on said bracket, a gear on the thread-guide shaft operatively connected with a gear on the driving-shaft, a spindle-support rotatively mounted on the 90 projection from the other side of said standard, a spindle mounted in the support and having a gear operatively connected with a gear on the driving-shaft, and means for maintaining one of said brackets in a position once 95 attained in its swinging movement.

2. In a machine for winding thread or the like, a standard, a main shaft mounted in the standard, means for driving the main shaft, a projection extending from each side of the 100 standard and each located opposite the other, a swinging bracket located on one of said projections, a thread-guide shaft and thread-guide mounted on said bracket, operative connections between the thread-guide shaft and driving-shaft, a spindle-support rotatively mounted on the projection from the other side 105 of the standard, a spindle mounted in the support, operative connections between the spindle-support and driving-shaft, and means 110 for maintaining one of said brackets in a position once attained in its swinging movement.

3. In a machine for winding thread or the like, a standard, a main shaft mounted in the standard, means for driving the main shaft, 115 a projection extending from each side of the standard and each located opposite the other, a swinging bracket located on one of said projections, a thread-guide shaft and thread-guide mounted on said bracket, operative connections between the thread-guide shaft and driving-shaft, means for controlling the swinging movement of the thread-guide bracket in either direction, a spindle-support rotatively mounted on the projection from the other side 120 of the standard, and operative connections between the spindle and driving-shaft.

4. In a machine for winding thread or the like, a standard, a main shaft mounted in the standard, means for driving the main shaft, 125 a projection extending from each side of the standard, a swinging bracket located on one

of said projections, a thread-guide shaft and thread-guide mounted on said bracket, operative connections between the thread-guide shaft and driving-shaft, a spindle-support rotatively mounted on the projection from the other side of the standard, a spindle mounted in the support, operative connections between

the spindle and driving-shaft, and means for maintaining the spindle-support in a position once attained in its swinging movement.

DICKERSON G. BAKER.
